(57) **CLAIM**

The ornamental design for a connector, as shown and described.

DESCRIPTION

FIG. 1 is a front perspective view of a connector showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines represent boundaries and form no part of the claimed design.

The design is shown with a symbolic break in its length. The appearance of any portion between the break lines forms no part of the claimed design.

1 Claim, 7 Drawing Sheets(56)
